[57] CLAIM

The ornamental design for a hub for a vehicle wheel, as
shown and described.

DESCRIPTION

FIG. 1 is a rear perspective view of a hub for a vehicle
wheel showing my new design;
FIG. 2 is an exploded front perspective view thereof;
FIG. 3 is a rear elevational view thereof;
FIG. 4 is an enlarged front elevational view thereof;
and
FIG. 5 is an enlarged left side elevational view thereof,
partially in cross section, taken along section lines 5—5
of FIG. 4.
